CLAIM

(22) Filed: **Jan. 30, 2002**

The ornamental design for a surface configuration of a rear bumper for a vehicle, as shown and described.

(30) Foreign Application Priority Data

DESCRIPTION

Jul. 30, 2001 (DE) 401 06 965

This application is related to co-pending U.S. application Ser. No. 29/154,716, of the inventor, filed on even date herewith and entitled “Surface Configuration of a Vehicle, Toy and Miscellaneous Consumer Products Incorporating the Design.”

(51) LOC (7) Cl. **12-16**

FIG. 1 is a left, perspective view of a surface configuration of a rear bumper for a vehicle according to my novel; FIG. 2 is a front view of a surface configuration of a rear bumper for a vehicle according to my novel design; and, FIG. 3 is a left side view of the surface configuration of a rear bumper for a vehicle according to my novel design. The broken lines included depict environment and are not part of the claimed design. Also enclosed is a set of photographs of an embodiment of my invention.
